Atty's.

UNITED STATES PATENT OFFICE.

CHARLES HERMAN MILLER, OF CHICAGO, ILLINOIS, ASSIGNOR, BY MESNE ASSIGNMENTS, TO THE LIQUID CARBONIC CORPORATION, OF CHICAGO, ILLINOIS, A CORPORATION OF DELAWARE.

SIRUP-CHARGING APPARATUS.

Application filed January 29, 1923. Serial No. 615,486.

The invention relates to improvements in apparatus for use in bottling works and other places where soda water, and other liquids are manufactured and bottled in preparation for delivery to customers, and the purpose of the invention is to provide means for measuring and discharging into bottles the sirup or other flavor or extract which is used in the formation of the beverages. The principal object of the invention is to provide improved means for measuring a definite charge of sirup and discharging it into a bottle. A further object is to provide means for measuring and discharging the sirup through a tube extending through a wall of the containing vessel, without employing any movable parts extending through that wall. Other objects relating to various features of construction and arrangement will appear more fully hereinafter.

The nature of the invention will be understood from the following specification taken with the accompanying drawings in which one embodiment is illustrated. Fig. 1 of the drawings represents a vertical section through the central part of the apparatus, certain parts thereof being shown in elevation; and Fig. 2 shows a detail section on the line 2—2 of Fig. 1.

As illustrated in the drawings the invention comprises a circular tank or vessel 10 which is adapted to contain the sirup 11, which is to be measured and discharged into the bottles. This vessel is mounted on a standard 12 which is capable of being adjusted vertically by means of a screw 13 and a hand wheel 14 in order to regulate the height of the vessel to permit the filling of different sizes of bottles. The bottles 15 are mounted on standards 16 carrying suitable devices 17 to engage the lower ends of the bottles, and these standards 16 are adapted to be moved vertically in order to bring into communication with the necks of the bottles, the tubes through which the sirup is discharged from the vessel 10. A series of bottle supports 16 may be distributed in a circle beneath the sirup containing vessel and a number of discharge openings may be provided so that a plurality of bottles may be charged with sirup simultaneously or successively. For the purpose of indicating the relative movements of the bottles with respect to the sirup containing vessel, one of the bottle supports

is shown in its lower position while another bottle support is shown in its uppermost position. In practice it may be preferable to move the bottles upwardly in succession by any suitable means adapted for that purpose. For example, the movable bottle supports 16 may be plungers mounted in cylinders 17 into which compressed fluid may be introduced through pipes 18 controlled by valve mechanism 19.

The sirup is discharged from the vessel 10 through stationary tubes 20 which extend downwardly through openings in the depressions 21, which are formed in the lower wall of the vessel. The nuts 22 serve to secure the tubes securely in position so that there is no movement of the tubes with respect to the wall of the tank 10 and no possibility of leakage of the sirup downwardly around the tubes. The tubes extend upwardly above the upper level of the sirup 11 and charges of the sirup are measured and discharged into these tubes at their upper ends by means of cups 23. These cups are mounted to slide vertically on the tubes 20 which pass through the hubs 24 thereof. The hubs have rubber bushings 24^a mounted therein to provide a close fit on the hubs.

The hubs 24 are provided on their outer sides with annular grooves 25 adapted to be loosely engaged by the forked extremities 26 of the rods 27 which extend vertically at the sides of the cups 23. The loose engagement of the extremities 26 of the rods 27 with the grooves in the hubs 24 permits such adjustment of these members as may be necessary toward the upward movement of the cups. Each rod 27 is connected at its upper end by a transverse member 28 to the upper end of another vertical rod 29, which extends downwardly and is slidably mounted in a sleeve 30 secured in the lower wall of the tank 10. The nuts 31 engage the lower threaded extremities of the sleeves 30 and the rods 29 extend downwardly through these sleeves with their lower ends secured to the blocks 32 which extend transversely from these rods and which have openings, therethrough adapted to permit a sliding engagement with the downwardly projecting portions of the tubes 20. A coil spring 33 is mounted on each rod 29 between the nut 31 and the block 32 so that the blocks are normally forced downwardly to the position illustrated at the left side of the drawing,

the extent of this movement being limited by the engagement of the member 28 with the upper end of the sleeve 30. Each of the blocks 32 is provided on its under side with a funnel-shaped member 35 adapted to receive the neck of the bottle when the bottle is thrust upwardly by the movement of the supporting member 16. A washer 36 of rubber or the like is mounted at the upper end of the guiding member 35 to engage the end of the bottle around the opening therein and a small bleed hole 38 leads through each block 32 and through the washer 36 to the open end of the bottle to permit the air therein to escape as the sirup is discharged into the bottle through the tube 20. When the bottles are moved upwardly by the upward movement of the supports 16, the bottle necks engage the funnel-shaped member 35 adapted to receive the neck of the bottle when the bottle is thrust upwardly by the movement of the supporting member 16. A washer 36 of rubber or the like is mounted at the upper end of the guiding member 35 to engage the end of the bottle around the opening therein and a small bleed hole 38 leads through each block 32 and through the washer 36 to the open end of the bottle to permit the air therein to escape as the sirup is discharged into the bottle through the tube 20. When the bottles are moved upwardly by the upward movement of the supports 16, the bottle necks engage the funnel-shaped guiding members 35 and the continued movement of the bottle supports causes the blocks 32 to slide upwardly on the tubes until the tubes project downwardly into the bottles as shown at the right hand side of the drawing. The upward movement of the blocks 32 carries upwardly the measuring cups 23 through the operation of the rods 27 and 29, and these cups having become filled with sirup when they were immersed in the body of the sirup in the tank 10, are emptied into the tubes 20 after they have passed above the upper surface of the sirup in the vessel to a sufficient degree to bring the upper ends of the tubes downwardly below the level of the sirup in the cups and preferably into the hubs 24 on the under side of the cups, as shown at the right hand side of the drawing. In this way the sirup flows downwardly through the tubes 20 into the bottles 15 and a definite charge of sirup is placed in each bottle without the possibility of any leakage of the sirup occurring from the vessel 10.

The sirup is supplied to the vessel 10 through a pipe 40 which extends into a sleeve 41 secured to a cover 42 carried by the brackets 43 which project laterally from opposite sides of the vessel 10. The pipe 40 communicates through a connecting pipe 44 with a chamber 45 which is formed in the cylindrical member 46 secured to the lower end of the connecting pipe. The discharge opening 47 leading from the lower end of this chamber is con-

trolled by a valve 48 having a downwardly projecting stem 49 arranged to be operated by a lever 50 which is pivoted on a bracket 51 and adapted to engage the lower end of the valve stem. The other end of the lever engages an under-surface 52 of a float 53 which rests on the sirup 11 in the containing vessel. When the level of the sirup falls to a predetermined limit, the float operates the lever 50 to open the valve 48 and permit a further supply of sirup to flow into the vessel. The depressions 21 in the lower wall of the vessel are provided with drain cocks 54 through which the sirup can be completely drained from the vessel when desired.

Although I have shown and described a single embodiment of the invention for purposes of illustration, it will be understood that it may be constructed in various other forms without departing from the scope of the appended claims.

I claim:

1. In an apparatus of the class described, a vessel for containing sirup, a tube fixed in the wall of said vessel by a fixed fluid tight joint and extending above the level of the sirup therein, a measuring cup slidably mounted on said tube and adapted to discharge its contents through said tube when elevated above the level of said sirup, means for moving a bottle into communication with said tube on the outer side of said vessel, a guiding member adapted to be engaged by said bottle and means actuated by said guiding member for moving said measuring cup to its discharging position.

2. In an apparatus of the class described, a vessel for containing sirup, a vertical tube extending through the lower wall of said vessel and having a fixed fluid tight joint with said wall, said tube terminating above the level of the sirup in said vessel, a cup having its lower wall slidably engaged by said tube, a sleeve having a fixed fluid tight joint with the lower wall of said vessel and terminating above the level of the sirup therein, a rod slidably mounted in said sleeve and connected above said sleeve to said cup, means for moving a bottle into communication with the lower end of said tube, and means actuated by the movement of said bottle for actuating said rod to elevate said cup into position to discharge its contents into the upper end of said tube.

3. In an apparatus of the class described, a sirup container, an unobstructed conduit leading from an unobstructed outlet above the level of the sirup in said container to a filling station and having a part thereof fixed in the lower wall of said container, means for moving a vessel to the filling station and into charging position relative to said conduit, means, including a measuring cup movable along said conduit, located in said container for segregating a predetermined quota

from the body of the sirup therein, and means, including a vessel guide and an actuating arm connected to said cup and guide, controlled by the movement of said vessel for discharging said quota unobstructedly into and through said conduit to the vessel as said cup is raised into communication with said outlet.

4. In an apparatus of the class described, 10 a sirup container, a conduit leading from an unobstructed outlet above the level of the sirup in said container to a filling station and extending through the lower wall of said container and having a fixed fluid-tight joint 15 with said wall, means for varying the elevation of said lower wall to vary the discharge

end of said conduit, means for moving the vessel to the filling station and into alignment with the discharge end of said conduit, means, including a cup, normally located within the 20 body of the fluid in said container for segregating a predetermined quota from the fluid therein, said cup being slideable along said conduit to said outlet, and actuating means, including a guide and actuating rod 25 associated therewith, controlled by the movement of the vessel to the filling station for sliding said cup vertically along said conduit to said outlet to discharge said quota through said conduit to said vessel.

CHARLES HERMAN MILLER.
